BEADED MOCK WELTING FOR MCKAY
TYPE FOOTWEAR

Charles F. Batchelder, Jr., Milton, and Lothrop Withington, Jr., Brookline, Mass., assignors to Wright-Batchelder Corporation, Boston, Mass., a corporation of Massachusetts

Application June 30, 1950, Serial No. 171,286

1 Claim. (Cl. 36—78)

1

Our present invention relates to beaded mock welting and more particularly to an ornamental and seam-filling beaded mock welting adapted for use with footwear of the McKay type of construction, and especially designed so that the bead will be automatically forced against the shoe upper by the normal pressure of a foot in the finished shoe.

At present, in footwear of the several McKay types in which the outsole, or the outsole and McKay welt or midsole, are united to a pre-lasted upper and insole by thru-and-thru stitching, it is generally found that the inseam stitching has a tendency to show or "grin" and thus detract from the appearance of the finished shoe. Such stitch "grinning" becomes further apparent in McKay footwear after the shoes have been worn for some time, as the upper tends to stretch away from the sole, thus presenting a most objectionable appearance.

It is to obviate this difficulty, therefore, and to assure an attractive appearing shoe that we have developed our novel beaded mock welt which is appropriately designed to be incorporated in any and all types of McKay shoes.

Heretofore, various efforts have been made to employ devices which would conceal the inseam stitches to prevent them from showing, but such prior devices have included extra strips, made of rubber or the like, which have proven unsatisfactory in use and expensive in cost, and also rubber rapidly deteriorates.

We appreciate that welts for use in Goodyear welt footwear have been made with beading as an integral part thereof for purposes of ornamentation, and even beaded strips alone, but as far as we are advised no beaded mock welting has heretofore been developed that may be effectively applied to footwear of the McKay type of construction.

From the experience gained in extruding resilient and stitch-retaining plastic welting for Goodyear welt shoes, we have determined that any shape of configuration of such plastic material may readily and accurately be supplied. Accordingly, for specific adaption to McKay footwear, we have designed a novel and useful beaded mock welt which can be applied to any shoe of McKay type construction, combines ornamental and seam-filling characteristics, and is so arranged that the bead portion thereof will be automatically held under pressure against the outside of the shoe upper.

In carrying out our invention, we prefer to arrange our mock welt with a thin stitch-retaining body portion suitably tapered to appro-

priately fill in the seam between the upper and the outsole, welt, or midsole. Integral with the body portion and upstanding therefrom substantially at right angles, we devise our novel curved bead, formed with a convex outer surface which depends slightly below the lower surface of the body to provide a tensioning rib portion, and with a concave inner surface of proper contour to approximate that of the marginal edge of a shoe upper, the top of said concave surface merging with the upper end of said convex surface to afford an inturned flange to bear tightly and snugly against the outer surface of the upper.

15 We find that the combination of the resilient characteristics of the material and the construction of the bead is particularly effective in causing our mock welt to closely hug the upper when applied to a shoe, as downward pressure

20 exerted on the upper surface of the body portion will apply force on the lower rib of the bead, thus setting up a rotary moment, thereby forcing the inturned flange against the upper and retaining the same in pressured contact with the upper.

25 Inasmuch as we prefer to make our novel mock welting of synthetic plastic material, we are enabled to turn out a uniform product, at an economical cost, and of any desired color.

30 In addition, the inherent resilience of such material is peculiarly suited to an ornamental, moisture-proof, and seam-filling beaded mock welt to improve the appearance, fit, and comfort of the footwear of McKay type construction.

35 Further features, objects, and details of construction will be hereinafter more fully pointed out in the accompanying description and more clearly defined in the appended claim.

40 Referring to the drawings showing a preferred embodiment of our invention:

Fig. 1 is a perspective view of a strip of our novel beaded mock welting;

Fig. 2 is a fragmentary cross-sectional view illustrating our novel mock welt, with the bead 45 slightly overdrawn, applied to a McKay type shoe embodying a welt and outsole construction;

Fig. 3 is a fragmentary cross-sectional view illustrating our novel mock welt with the bead slightly overdrawn, applied to a McKay type shoe 50 having a midsole and outsole construction, and

Fig. 4 is a fragmentary cross-sectional view illustrating our novel beaded mock welt, with the bead slightly overdrawn, applied to a nailed McKay shoe.

55 As shown in the drawings, our novel beaded mock welt, designated generally as 10, consists

in a unitary strip of resilient synthetic plastic material especially designed with a relatively thin attaching body portion 11 and an ornamental and seam-filling bead portion 12 integral with said body 11 and curved upwardly at substantially right angles thereto.

The body portion 11 is preferably arranged with an increasing widthwise taper from the inner edge to the points on its upper and lower surfaces where the same meet the corresponding ends of the bead 12.

Such body 11 presents an ideal stitching surface, and the taper enables it to be more easily guided into stitching position and to be more snugly fitted in the seam between the outsole and upper, welt and upper, or midsole and upper, depending on the type of McKay construction involved.

The bead 12 is of greater thickness than the body 11 and designed with convex exterior and concave interior surfaces, the curves of said surfaces being substantially parallel thru the medial portion of their respective arcs, and the exterior surface having inturned upper and lower edge portions to provide said bead 12 with a lower pressure-leverage rib 14 and an upper contacting flange 15, as shown. The bead 12 has been thus arranged so that downward pressure on the body portion 11 adjacent the rib 14 results in corresponding reaction on the rib 14 to cause the flange 15 to be automatically pressed in a lateral direction against the upper.

In Figs. 2, 3, and 4 we have illustrated our beaded mock welt in attached relation with several modifications of McKay shoe construction. In each of such modifications an upper 16, having the usual lining 17 attached therein, is lasted to an insole 18, which lasting may be effected by tacking, stapling, or, as here shown, by cementing.

In Fig. 2 the upper 16 and the insole 18 are assembled on a last, and cement-lasting together. Thereupon, the last is withdrawn, and our mock welt 10, together with the McKay welt 20, simultaneously fed about the lasted edge of the upper 16 by suitable guides as the thru-and-thru inseam stitching, indicated at 21, is set.

Following the inseam-stitching operation, the outsole 22 is then applied and secured by a line of outseam stitching 23 thru the welt 20 and outsole 22 adjacent the outer edges thereof. The usual finishing operations are then performed and the shoe completed.

In Fig. 3, we have depicted our beaded mock welt 10 applied to a McKay shoe of the type embodying a midsole and outsole construction. In this form, the upper 16 and insole 18 are assembled on a last as above, cement-lasting together, and the last withdrawn. Thereupon, our mock welt 10 is fed by suitable guides about the lasted edge of the upper 16 as the thru-and-thru stitching 26 is set, uniting the insole 18, upper 16, and body portion 11. A midsole 25 is then prepared and secured to the above by a further line of inseam stitching 27, after which an outsole 28 is incorporated therewith by means of outseam stitching 29 set thru the outer edges of said midsole 25 and outsole 29. As above, the usual finishing operations are then performed and the shoe completed.

In Fig. 4, we have shown our beaded mock welt 10 applied to a shoe of the so-called straight McKay type of construction. Similarly, in this method the upper 16 and insole 18 are first assembled on a last and bonded together by cement-

lasting. The last is then withdrawn, and our mock welt 10 suitably guided about the lasted edge of the upper 16 as the thru-and-thru inseam stitching, indicated at 30, is set, thus uniting the upper 16, insole 18, and body 11 of our mock welt 10.

As thus far assembled, the shoe is thereupon re-lasted and the outsole 31 attached thereto by a line of tacks 32 which are readily driven thru the sole 31, body 11 of the mock welt 10, upper 16 and insole 18, and clinched over against the last bottom, as shown. And, again, as in the other forms described, the shoe is now in readiness for the usual finishing operations.

From the foregoing, it will be apparent that our invention may be readily adapted to various types of McKay shoe constructions, functioning as an ornamental, seam-filling, and moisture-proof element. The tapered body portion 11 is ideally arranged to fill the inner space between the lasted upper and the sole elements, while the construction of the bead 12 adequately fills the outer seam therebetween and conceals the stitching. As shown in Figs. 2, 3 and 4, the tightening action of the stitches 21, 26, and 30, respectively, is sufficient to flatten out the rib 14, thus creating enough pressure on the flange 15 so that it will hug the marginal edge of the upper 16 in moisture-tight association. The resilient and yielding characteristics of the synthetic plastic material are of the utmost importance in making our beaded mock welt so useful, serviceable, efficient, and comfortable to the wearer, and the fact that such material is waterproof and may be produced in any color adds to the all-around value of our product.

While our beaded mock welt, as above explained, is directed for use with footwear of the McKay type of construction, we do not wish to be limited thereby as our invention could well be adapted to other types of shoe construction.

We claim:

A resilient beaded mock welt of the kind described for use in making McKay type footwear, comprising a tapered stitch-receiving body portion and a seam-filling bead portion formed substantially at right angles to said body portion and having a convex exterior surface and a concave interior surface said surfaces being substantially parallel throughout the medial portion of their respective arcs, the upper end of said convex surface merging with the top of said concave surface constituting an inturned ridge, and the lower end of said convex surface depending slightly below the bottom of said body portion to provide a leverage rib to force the in-turned top ridge in pressured contact with the upper of a shoe to which the beaded mock welt is attached.
